(57) **CLAIM**

I claim the ornamental design for a carburetor vent manifold, as shown and described.

DESCRIPTION

FIG. 1 is an elevational view from the side of a carburetor vent manifold;

FIG. 2 is perspective view thereof;

FIG. 3 is another perspective view thereof;

FIG. 4 is another perspective view thereof; and,

FIG. 5 is another perspective view thereof.

The broken lines showing of the environment is for illustration purposes only and forms no part of the claimed design. The broken lines which define the boundaries of the claimed design form no part thereof.
